UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

ELECTRIC CONTROLLER.

1,423,126.

Specification of Letters Patent. Patented July 18, 1922.

Application filed November 21, 1916. Serial No. 132,686.

To all whom it may concern:

Be it known that I, NILS D. LEVIN, a citizen of the United States, residing at Columbus, in the county of Franklin and the State

5 of Ohio, have invented certain new and useful Improvements in Electric Controllers, of which the following is a specification, reference being had therein to the accompanying drawing.

10 The present invention relates to certain new and useful improvements in electric controllers adapted to the control of electric locomotives. The object being to produce a controller of large capacity, extreme durability, and of convenient arrangement of parts.

One object is to produce an improved arrangement of blow out magnets adapted to effectively extinguish the arcs formed between the contact segments and the brushes 20 by the rupture of heavy currents of electricity.

A further object is to provide an improved mounting for the blow out magnets by which 25 they may be conveniently swung aside to admit of the inspection and adjustment of the brushes and contact segments.

A further object is to provide an improved arrangement of arc deflecting plates for the 30 prevention of the formation of arcs between adjacent brushes.

These and other objects will appear in the following specification wherein reference is had to the accompanying drawings of 35 which—

Fig. 1 is a front elevation of my controller, the cover being removed and certain parts being broken away to reveal other parts.

Fig. 2 is a cross section taken on the lines 40 A—A of Fig. 1.

Fig. 3 is a cross section taken on the line B—B of Fig. 1.

Fig. 4 is a diagram of the electric circuits of a three motor locomotive including my 45 improved controller.

Like numerals refer to similar parts in the several figures.

The operative parts of the controller are mounted within a casing comprising a back 50 plate 1, cast integral with the bottom 2, and having at its upper edge lugs 3 to which is secured the top plate 4 by convenient ma-

chine screws 5. A sheet steel cover 6 engages the side flanges 7 of the back plate and is held in place in any preferred and 55 suitable manner.

The controller comprises a rotatable commutating cylinder having renewable contact segments adapted to contact with stationary brushes to connect the conductors of the locomotive into suitable combinations of circuits to effect the starting and stopping and to regulate the speed of the motors, and a rotatable reverse cylinder having contact plates adapted to contact with stationary brushes 60 to connect the said conductors into suitable combinations to control the direction of rotation of the armatures and to connect the motors in series or in parallel with each other. Suitable interlocking devices are provided to prevent the rotation of either cylinder when the other is in a position such as 65 will produce an undesirable combination of circuits.

The commutating cylinder is of the well 70 known construction in which a plurality of spider sections 15 are mounted upon a square shaft 16 from which they are electrically separated by suitable insulation 17. The spider sections are clamped between the 75 clamping collar 18, pinned to the shaft 16 near its upper end, and a similar collar 19, pinned near the lower end of the said shaft. Suitable insulating washers separate the spider sections from each other and from the 80 clamping members. To the arms of the spider 15 are attached contact segments 21 of such length and position as to contact with their corresponding brushes 22 at the appropriate steps of the rotation of the cylinder 85 to produce the desired combination of connections.

The shaft 16 is square throughout the greater part of its length, and is turned round near each end to form journals which are rotatable in journal bearings formed in the top and bottom plate of the controller casing in the manner common in controller practice. A convenient handle 27, attached to an extension of the shaft 16 above the 90 top plate 4, affords means for the rotation of the cylinder.

To simplify the matter of repair and renewals of parts, it is important that the

parts which are subject to the most frequent renewal shall be reduced to the least possible variation of size and shape, and for this reason it is especially desirable that 5 all of the brushes shall be alike. As the currents flowing in some of the circuits of such a locomotive as is contemplated in connection with such a controller are several times greater than in others, it is apparent 10 that if all of the brushes were made large enough to carry the heavier currents the controller would be unduly cumbersome and expensive. I have, therefore, arranged certain of the brush holders with two or more 15 brushes, connected in parallel, thereby securing conductivity proportionate to the requirements of the circuit with the additional advantage of the greater reliability of divided contacts and with uniform units 20 adapted to the circuits with which they are used.

In order that the overall length of the controller may be kept within the space available upon the locomotive, I have arranged 25 the commutating cylinder brushes in two oppositely disposed rows, one at each side of the commutating cylinder. The brushes 22 are pivotally mounted upon the brush holder casting 35 secured to a wooden 30 mounting strip 36 attached to the back plate of the controller casting, and are resiliently held in contact with the segments of the cylinder by suitably arranged compression springs 38 in the manner well understood in 35 the art. Each brush 22 is connected by a flexible copper conductor 39 to a terminal connector 40 having a stem 41 which extends through an appropriate aperture in the casing of the controller and is connected 40 to the conductors of the circuits of the locomotive by clamping nuts 43.

The blow out magnets are two cylindrical cores 49 extending vertically in front of the commutating cylinder and brushes, equidistant from the central vertical plane of the cylinder, and of equal length therewith. Upon these cores are placed insulating tubes 50, and upon these are wound the conductors 51 in such manner that air space is 50 maintained between adjacent turns. The coils thus formed are protected by shields 52 composed of non-combustible insulating material. At each end the conductors 51 are soldered to thimbles 53 having flanges 54 secured to the arms 55 to support the coils and form the electrical connection by which said coils are connected into the circuits of the locomotive.

By the construction above described I 60 have provided, adjacent each row of contacts between the brushes 22 and the commutating segments 21 a powerful magnet having highly localized poles of opposite signs at its ends, by which is produced an 65 intense external field in which the lines of

force flow substantially parallel with the length of the magnet. By the uniform distribution of the conductor 51 over the entire length of the core 49 a greater degree of magnetization is obtained with a given 70 number of turns of the conductor, and a more strictly localized polarity is produced than with blow out magnets such as have been heretofore constructed.

The supporting arms 55 are provided at 75 their right hand ends with downwardly projecting studs 55^a adapted to engage with suitable apertures in the hinge posts 56 which are mounted on the mounting strips 36. On the left hand end of the supporting 80 arms 55 are formed flat lugs 57 adapted to be secured by suitable machine screws 58 to the flat heads of the terminal posts 59, mounted similarly to the brush holder terminals, and connected in a similar manner by terminal clamps 60 with the conductors of the locomotive. The above described arrangement is adapted to form the necessary electrical connections and to securely support the blow out magnets in 90 working relation with the commutating cylinder and with the brushes. By the removal of the screws 58 the arms 55, together with the blow out magnets, may be rotated on the hinge posts 56 to permit inspection and 95 adjustment of the brushes and commutating segments. After such rotation these parts may, if desired, be lifted to disengage the studs 55^a from the posts 56 to allow the removal of the blow out magnets from the 100 controller.

Between adjacent groups of brushes are placed plate 61 of non-combustible insulating material, to insure against the short circuiting of the controller by the jumping 105 of the arcs from one brush to the next. These arc deflectors 61 extend from the transverse center line of the blow out magnets to the back wall 1 of the casing of the controller, and from one mounting strip 36 110 to the other, and are notched around the cylinder 15 to admit their being inserted or withdrawn from the front of the controller. Their forward edges are notched to fit closely around the shield 52 of the blow out magnets which, when in operative position, hold them securely in place. The wooden mounting strips 36 are protected by plates 62 of non-combustible insulating material to which are attached shield blocks 115 63 of the same material to afford additional protection to the hinge members of the brushes, and to hold the arc deflectors 61 in spaced relation to each other.

The circuits of the controller are so arranged that the heaviest currents, which produce the strongest arcs, flow through the brushes at the top and bottom extremities of the controller where the lines of force of the external field are densest, and the 120 125 130

direction of the current at these points, and through the coils of the blow out magnets, are such that the arcs are blown outwardly along lines parallel with the deflector plates

5 61. Although the deflector plates are constructed of highly refractory material, and are not subjected to the direct burning action of the arcs, they are subjected to gradual deterioration which necessitates their re-

10 newal at more or less frequent intervals, and the separate removability of these plates, and their ready accessibility, contributes greatly to increase the convenience and economy of such renewal.

15 The reverse cylinder is of the construction commonly used in controllers of this class, and consists of a wooden cylinder 63 mounted concentrically upon a shaft 66 which is journaled in the top and bottom 20 plates of the controller casing. Upon the surface of this wooden cylinder are fixed contact plates 67 which are adapted to contact with brushes 68 to connect them together in such combinations as may be necessary 25 to produce the desired circuits in the wiring of the locomotive. Longitudinal grooves 69 admit of connecting bars 70 to connect together plates which are not contiguous where such connections are desirable.

30 Such controllers are especially adapted to use upon electric locomotives designed for use in coal mines, and similar service, requiring extremely heavy current, and having very limited space available for controlling apparatus.

35 Having now described the details of the construction of my controller, its operation will be more clearly understood from the explanation of the diagram of a locomotive 40 in which such a controller is used, but it must be understood that other combinations of circuits can be made with the same apparatus without departure from the spirit of my invention.

45 In the diagram shown in Fig. 4 the commutating cylinder is represented by a group of rectangles representing the contact segments, those numbered 21^a are attached to the uppermost spider section, those numbered 21^b, 21^c, 21^d and 21^e are on the middle spider section, and that marked 21^f is on the lowest section. The segments of each section are connected together electrically 50 through the body of the spider and are insulated from the segments of another section. The commutating cylinder brushes are represented by the rows of rectangular figures arranged at both sides of the commutating segments, the length of the rectangle 55 being proportional to the number of brushes connected in parallel held by the respective brush holders. The contact plates of the reverse cylinder are arranged in four vertical rows, representing the four operative 60 positions of the cylinder, and marked PA

(parallel ahead), SA (series ahead), SR (series reverse) and PR (parallel reverse). Suitable resistance grids 90 are arranged in groups to produce the electrical resistance appropriate to the purpose intended. 70

As shown in the diagram, current is derived through one or other of the two trolley poles 91 from a trolley wire (commonly of positive polarity) stretched conveniently above the track upon which the locomotive 75 operates. These trolley poles are connected through the usual plug connectors 92 with a single pole double throw switch 93 by which the trolley pole not in active service is disconnected from the circuits of the locomotive. 80 From the trolley switch 93 the circuit passes through the fuse 94 to the contacts of the plunger switch 95 outside of the controller, by which the final main break is effected. From the plunger contacts the circuit passes through the two blow out coils 51 in parallel, and thence to the commutator brush R⁷ of the controller. From this point a branch conductor leads to the point R⁷ in 85 the resistance 90. A branch conductor is taken off the main circuit at the point 96 between the fuse and the plunger which leads to the brush 97 of the commutating cylinder, and from the companion brush 98 is lead 90 through suitable resistance 99 to the operating solenoid 100 of the plunger, to the ground (which is commonly of negative polarity). 95

When the commutating cylinder is moved to the first step of its rotation the contact segments 21^a will contact with the brushes R⁸, and with the brushes P, F, and I, but as yet there is no current in any of the circuits of the locomotive. At the same time the segments 21^f will contact with the brush 98. At 100 the second step the segment 21^f will contact with the brushes 97 and 98 closing the circuit through the solenoid 100 to cause the contact 95 to close, sending current into the circuits. At the same time the segments 21^e 105 contacts with the brushes R¹. The path of the current will then be from the plunger 95 through the blow out coils 51 to the point R⁷ of the resistance, traversing the entire length of the resistance to the brush holder R⁸, through the segments 21^a, to the brushes 110 P, F, and I. The conductors from the brushes P and F lead to the correspondingly marked brushes of the reverse cylinder which, at the position SA find no contact plates. From the brush I the circuit is to 115 the point I of the No. 1 motor, through its field to the point C, from thence to the brush C, to the brush D, to the point D of the motor, through the armature and interpole windings to the point B, to the brush B, 120 brush E, point E of the No. 2 motor, through the field to point C, to brush G, to brush H, point H of the motor, through the armature and interpole windings to the point L, brush 125 L, brush O, point O of the No. 3 motor, 130

through the armature and interpole windings to point M, to brush M, to brush N, to point N, and through field to ground. By this combination a reduced current will flow 5 through the three motors in series causing their armatures to revolve in a direction to move the locomotive ahead.

As the commutating cylinder is rotated through its successive steps the segments 21^a, 10 21^b, and 21^c are brought successively into contact with the appropriate fingers to short circuit portions of the resistance, and at the last step all of the resistance is cut out of the circuit, allowing the full strength of 15 the current to flow through the motors.

When the cylinder is rotated in the reverse direction the resistance is cut into the circuit in the same progressive manner that it had been previously cut out, and when the last 20 step is taken the current is cut out of the solenoid 100 to allow the contact 95 to open, producing the final main break of the circuit to stop the locomotive. As the contact is broken between each successive brush and 25 its corresponding segments during the reverse rotation of the cylinder there are formed electric arcs which it is the province of the blow out magnets to extinguish. From Fig. 4 it will be seen that in every instance 30 the current flows from the brushes of the right hand row to the segments of the commutating cylinder, and from the segments of the commutating cylinder to the brushes of the left hand row. As the conductor 51 is 35 wound upon the core 49 in such a direction that the magnets will have north polarity at the top, the lines of magnetic force flow downwardly through the external field. When the contact segments move from the 40 brushes of the left hand row the current will travel across the intervening gap from left to right intersecting the lines of magnetic force in a direction to cause the resultant arc to be blown outward between the magnets 45 where there is ample space for the dissipation without injury to the parts of the apparatus. When the commutating segments pass from the brushes of the right hand row the current will travel across the intervening 50 gap from the left to the right intersecting the lines of magnetic force in a direction to be blown inwardly towards the cylinder 55 15. The arrangement of the parts however is such that at the left hand side of every commutating segment there is ample room for the dissipation of the arcs without injury to the parts of the apparatus.

What I claim is:

1. In a controller of the class described, 60 the combination with a rotatable cylinder, of contact plates carried by the cylinder, brushes adapted to contact with the plates, an elongated magnet core adjacent the points of contact of the brushes and having its 65 magnetic axis parallel with the axis of the

cylinder, and an insulated conductor wound upon said core.

2. In a controller of the class described, the combination with a rotatable cylinder, 70 contact plates carried by the cylinder, brushes adapted to contact with the plates, an elongated magnet core adjacent the points of contact of the brushes and having its magnetic axis parallel with the axis of the cylinder, and an insulated conductor 75 wound in a continuous coil upon the core.

3. In a controller of the class described, the combination with a rotatable cylinder, 80 contact plates carried by the cylinder, brushes adapted to contact with the plates, an elongated magnet core adjacent the points of contact of the brushes and having its magnetic axis parallel with the axis of the cylinder, an insulated conductor wound in a continuous coil upon the core, and a 85 noncombustible insulating shield arranged to protect said conductor from the injurious effects of the arcs formed at said contact points.

4. In a controller of the class described, 90 the combination with a rotatable cylinder, of contact plates carried by the cylinder, brushes adapted to contact with the plates, an elongated magnet core adjacent the points of contact of the brushes and having its magnetic axis parallel with the axis of the cylinder, an insulated conductor wound upon said core, and a cylindrical noncombustible insulating shield surrounding said conductor. 95

5. In a controller of the class described, the combination with a rotatable cylinder, 100 contact plates carried by the cylinder, brushes adapted to contact with the plates, an elongated magnet core adjacent the 105 points of contact of the brushes and having its magnetic axis parallel with the axis of the cylinder, an insulated conductor wound in a continuous coil upon said core, and a cylindrical noncombustible insulating shield surrounding said coil and longitudinally co-extensive therewith. 110

6. In a controller of the class described, the combination with a rotatable cylinder, 115 of contact plates carried by the cylinder, brushes adapted to contact with the plates, an elongated magnet core parallel with the cylinder adjacent the points of contact of the brushes, an insulated conductor wound upon the core, and supports for the magnet which also serve to connect the conductor of the coil with the conductors of the circuits. 120

7. In a controller of the class described, the combination with a rotatable cylinder, 125 of contact plates carried by the cylinder, brushes adapted to contact with the plates, an elongated magnet core parallel with the cylinder adjacent the points of contact of the brushes, an insulated conductor wound in a continuous coil upon the core, and supports 130

for the magnet which also serve to connect the conductor of the coil with the conductors of the circuits.

8. In a controller of the class described, 5 the combination with a rotatable cylinder, of contact plates carried by the cylinder, brushes adapted to contact with the plates, an elongated magnet core parallel with the cylinder, adjacent the points of contact of the brushes, an insulated conductor wound in a continuous coil upon the core, and supports 10 for the magnet which also serve to connect the conductor of the coil with the conductors of the circuits, said supports containing 15 hinges upon which the magnet may be swung aside to admit of inspection of the brushes and plates.

9. In a controller of the class described, the combination with a rotatable cylinder, 20 of plates carried by the cylinder, brushes adapted to contact with the plates, a blow out magnet comprising an elongated coil adjacent the points of contact of the brushes, and hinged members adapted to removably 25 support the magnet and to connect the conductor of the magnet with the conductors of the circuits.

10. In a controller of the class described, the combination with a rotatable cylinder, 30 of plates carried by the cylinder, two rows of oppositely disposed brushes adapted to contact with the plates, blow out magnets comprising elongated coils positioned adjacent the points of contact of each row of brushes, 35 and hinged members adapted to removably support the magnets and to connect the conductors of the coils with the conductors of the circuits.

11. In a controller of the class described, 40 the combination with a rotatable cylinder, of plates carried by the cylinder, a plurality of rows of brushes adapted to contact with the plates, blow out magnets comprising elongated coils positioned adjacent 45 the points of contact of each row of brushes, and hinged members adapted to removably support the magnets and to connect the conductors of the coils with the conductors of the circuits.

50 12. In a controller of the class described, the combination with a rotatable cylinder, of plates carried by the cylinder, brushes adapted to contact with the plates, an elongated blow out magnet adjacent to point of 55 contact of the brushes, and independently removable insulating plates between the brushes to prevent the formation of arcs between adjacent brushes.

13. In a controller of the class described, the combination with a rotatable cylinder, 60 of plates carried by the cylinder, brushes adapted to contact with the plates, independently removable insulating plates between the brushes to prevent the formation of arcs between adjacent brushes, an elongated 65 blow out magnet adjacent the points of contact of the brushes and adapted when in operative position to contact with the insulating plates and hold them in position.

14. In a controller of the class described, 70 the combination with a rotatable cylinder, of plates carried by the cylinder, brushes adapted to contact with the plates, and independently removable insulating plates between the brushes to prevent the formation 75 of arcs between adjacent brushes.

15. In a controller of the class described, the combination with a rotatable cylinder, 80 of plates carried by the cylinder, brushes adapted to contact with the plates, an elongated blow out magnet adjacent the points of contact of the brushes, insulating plates between the brushes to prevent the formation of electric arcs between adjacent brushes said plates being supported independently 85 of said blow out magnet and removable independently of each other.

16. In a controller of the class described, the combination with a rotatable cylinder of contact plates carried by the cylinder, a 90 plurality of rows of brushes adapted to contact with the plates, and blow out magnets comprising axially elongated coils positioned adjacent the points of contact of each row of brushes and having their magnetic axes parallel with the axis of said cylinder.

17. In a controller of the class described, the combination with a rotatable cylinder, 100 of plates carried by the cylinder, brushes adapted to contact with the plates, independently removable insulating plates between the brushes to prevent the formation of arcs between adjacent brushes, an elongated blow-out magnet removably supported adjacent the points of contact of the brushes and in position to prevent the removal of said insulating plates while said blow-out magnet is in operative position relative to said brushes.

In testimony whereof I affix my signature, in the presence of two witnesses.

NILS D. LEVIN.
